UNITED STATES PATENT OFFICE.

HARRY B. ROUSE, OF CHICAGO, ILLINOIS.

GAS-GENERATING APPARATUS.

No. 821,258.

Specification of Letters Patent.

Patented May 22, 1906.

Application filed October 20, 1905. Serial No. 288,645.

To all whom it may concern:

Be it known that I, HARRY B. ROUSE, a citizen of the United States, residing at Chicago, in the county of Cook and State of Illinois, have invented a certain new and useful Improvement in Gas-Generating Apparatus, of which the following is a full, clear, concise, and exact description, reference being had to the accompanying drawings, forming a part 10 of this specification.

My invention relates to apparatus for producing gas, and is of particular utility in connection with small gas plants that may be in use by unskilled or comparatively unskilled 15 people—such, for example, as house gas plants.

The invention is of particular service in connection with apparatus that is adapted to produce acetylene gas, and has for its object 20 the provision of absolute means for preventing explosion when the carbid-chamber is being replenished.

In the construction of the apparatus to which my invention relates there is employed 25 a chamber for the carbid that is located adjacent to the gas-reservoir, the carbid being automatically fed from the carbid-chamber to the gas-reservoir as required. The carbid-chamber is usually placed within the gas-

30 reservoir, the carbid feeding by gravity from the carbid-chamber to the gas-tank, the gate that controls the admission of the carbid to the gas-tank being automatically regulable.

In order that the carbid in the carbid-chamber may be replenished, a screw-plug or other 35 suitable gate is provided in the top wall of the carbid-chamber upon the removal of which the spout of a funnel may be inserted into the carbid-chamber to replenish the carbid

40 therein. Hitherto a lever device was normally disposed above this plug or gate in the carbid-chamber, so that the funnel could not be placed in position without moving this lever to one side, the lever being normally held

45 in place by a pin projecting from the screw-plug to hold the lever in a normal position. By lifting the lever from its normal plane it could override the pin in the plug, whereafter a spring was brought into play for the in-

50 tended purpose of frictionally engaging the lever with a part driven by the motor (usually a spring-motor) employed in feeding the carbid from the carbid-chamber to the gas-

55 tank with the end in view of preventing the continuation of the generation of gas within the gas-tank, which would find access through

the vent vacated by the threaded plug to prevent explosion. As a matter of fact, however, this construction has proven an insufficient safeguard, for many serious explosions 60 have occurred in spite of the precaution taken in this construction that have seriously maimed many people. The device of the prior art above described does not eliminate the menace to life because of defective construction, which it is the object of my invention to cure. One of the defects in the prior construction resided in the frictional engagement brought about by the aforesaid spring which was never sufficiently positive, par- 70 ticularly when the spring-motor was freshly wound, and therefore of high power. It will be apparent that the frictional or braking action is not a sufficient safeguard against the operation of the spring-motor when the plug 75 is removed. Moreover, in the hands of unskilled people the spring that was employed to bring about this frictional engagement was frequently stretched to such an extent as to be too weak to bring about the frictional 80 contact between the lever and the part driven by the spring-motor.

In practicing my invention I equip the lever with a stop or finger which engages a stationary step, whereby the extent to which 85 the lever may be moved in escaping the plug or the pin upon the plug may be limited, so that the "set" of the spring is not impaired. I also employ a stop or pin for the lever, which is preferably the same pin or stop 90 aforesaid that is brought directly into the path of a part driven by the spring-motor, such as the retarding-fan, when the spring co-operating with the lever is free to act, which freedom of action is afforded when the 95 lever is removed from engagement with the pin in the plug.

I will explain my invention more fully by reference to the accompanying drawings, in which—

100 Figure 1 is a view in elevation, with parts broken away, of the preferred embodiment of my invention; and Fig. 2 is a plan view of so much of the structure shown in Fig. 1 as is necessary to an understanding of the invention.

Like parts are indicated by similar characters of reference in both figures.

The gas-producing apparatus illustrated 110 includes a chamber *a* for containing some of the raw material, as calcium carbide, employed as an ingredient for producing the gas,

2
and a tank *b*, in this instance containing water into which material is fed from the chamber *a* and from which tank *b* the gas is supplied by any suitable means to the consuming devices. Some suitable and well-known feeding and governing apparatus is employed such as that diagrammatically indicated at *c*. A suitable motor device, such as spring-motor mechanism *d*, is employed for regulating the mechanism *c*, and as said motor feeding and regulating device is well known by those skilled in the art I do not deem a detailed description thereof to be essential. It will suffice to say that the spring-motor *d* through some device intervening between it and the mechanism *c*, such as the rod *e*, serves to govern the operation of the mechanism *c*, suited to the production of the gas and the corresponding rate of flow of the carbid from the carbid-chamber to the gas-tank, where the gas is produced as well as stored in the usual forms of apparatus. The element *e* is rotated by the spring-motor to effect the feed of the carbid from the carbid-chamber, to the gas-tank, and in accordance with the object of my invention I positively arrest the rotation or operation of this element *e* when the threaded plug *f* is removed for the purpose of inserting the spout of a funnel into the carbid-chamber to replenish the carbid within the chamber, the element *e* being arrested during the absence of the plug from its normal place. As was the case with the constructions of the prior art I employ a pin *g*, carried by and projecting above the plug *f*, and a broken lever *h*, pivoted at *i* and provided with a spring *k* for the purpose of enabling said broken lever to stop the motor mechanism *d* when said lever is disengaged from the pin *g*, normal engagement being maintained between said lever and pin by the spring *k*, because the pivot *i* is located between the ends of the lever *h*. In order to bring about disengagement between the elements *g* *h*, the element *h* has to be lifted from its normal plane at its free end to escape the top of the pin *g*, whereafter the front end of the lever may be moved with respect to the balance of the lever, as indicated in Fig. 2 in dotted lines, freely to permit the removal of the plug *f* and the insertion of the funnel. While the characteristics last described are possessed by devices as hitherto constructed, there was no provision made for limiting the extent to which the lever *h* might be moved in a counter-clockwise direction against the force of the spring *k*, except said spring itself, so that the set of said spring has hitherto frequently been destroyed, whereby said spring was prevented from moving the lever *h* with sufficient force to brake the operation of the motor, as a result of which structural defect the feeding device *c* was allowed to continue in operation while the plug *f* was removed, so that acetylene gas has on several occasions continued in generation and found

access through the opening at *f* in the carbid-chamber with disastrous consequences. In order to determine the limit to which the spring *k* may be stretched in effecting disengagement between the elements *g* *h*, I provide a stop *l*, that projects downwardly from the short end of the lever *h* and through the plane of the plate *m* of the mechanism *d*, said plate *m* being notched at *n*, so that a wall of the notch may constitute a limiting-stop for the finger *l* to prevent the excessive rotation of the lever *h* in a counter-clockwise direction, whereby the set of the spring *k* is maintained. When the lever has been thrown in the position indicated by dotted lines in Fig. 80 2, some finger, preferably the same finger *l*, is brought into the path of an element driven by the motor *d*, such as the retarding-fan *o*, and as the set of the spring *k* is insured the said finger *l* is bound to be thrown within the path of the fan *o*, whereby the operation of the feeding device *e* is arrested, while the lever *h* is in the position shown by dotted lines and can only be resumed when said lever is restored to the position indicated in full lines. 90

The parts *h* and *l* together constitute a member that is held in one position by the element *g* to remove said member from the path of the motor-driven element *o*, while the element *k* constitutes a means for bringing 95 said member into the path of said motor-driven element when the member is disengaged from the pin *g*.

Having thus described my invention, I claim as new and desire to secure by Letters 100 Patent—

1. A gas-producing apparatus including a tank, a supply-chamber, a supply gate or plug for charging the supply-chamber, a feeding device for controlling the admission of material from the supply-chamber to the tank, a motor governing the operation of the feeding device, a member adapted when in one position to be interposed in the path of an element driven by said motor and when in another position to be removed from said path, said gate or plug serving when in closed position to prevent said member from arresting the operation of the motor-driven element, and means causing said member to be 115 within the path of said motor-driven element when said member is free of said gate or plug.

2. A gas-producing apparatus including a tank, a supply-chamber, a supply gate or plug for charging the supply-chamber, a feeding device for controlling the admission of material from the supply-chamber to the tank, a motor governing the operation of the feeding device, a member adapted when in one position to be interposed in the path of an element driven by said motor and when in another position to be removed from said path, said gate or plug serving when in closed position to prevent said member from arresting 125 the operation of the motor-driven ele- 130

ment, and a spring causing said member to be within the path of said motor-driven element when said member is free of said gate or plug.

5. 3. A gas-producing apparatus including a tank, a supply-chamber, a supply gate or plug for charging the supply-chamber, a feeding device for controlling the admission of material from the supply-chamber to the 10 tank, a motor governing the operation of the feeding device, a member adapted when in one position to be interposed in the path of an element driven by said motor and when in another position to be removed from said 15 path, said gate or plug serving when in closed position to prevent said member from arresting the operation of the motor-driven element, a spring causing said member to be within the path of said motor-driven element 20 when said member is free of said gate or plug, and a stop limiting the movement of said member away from the path of said motor-driven element.

4. A gas-producing apparatus including a 25 tank, a supply-chamber, a supply gate or plug for charging the supply-chamber, a feeding device for controlling the admission of material from the supply-chamber to the tank, a motor governing the operation of the 30 feeding device, a member adapted when in one position to engage an element driven by said motor and when in another position removed from engagement with said motor-driven element, said gate or plug serving 35 when in closed position to prevent said member from arresting the operation of the motor-driven element, a spring causing said member to engage said motor-driven element when said member is free of said gate or plug, 40 and a stop limiting the movement of said member away from the path of said motor-driven element.

5. A gas-producing apparatus including a

tank, a supply-chamber, a supply gate or plug for charging the supply-chamber, a feeding device for controlling the admission of material from the supply-chamber to the tank, a motor governing the operation of the feeding device, a member adapted when in one position to be interposed in the path of an element driven by said motor and when in another position to be removed from said path, said gate or plug serving when in closed position to prevent said member from arresting the operation of the motor-driven element, means causing said member to be within the path of said motor-driven element when said member is free of said gate or plug, and a stop limiting the movement of said member away from the path of said motor-driven element.

6. A gas-producing apparatus including a tank, a supply-chamber, a supply gate or plug for charging the supply-chamber, a feeding device for controlling the admission of material from the supply-chamber to the tank, a motor governing the operation of the feeding device, a member adapted when in one position to engage an element driven by said motor and when in another position removed from engagement with said motor-driven element, said gate or plug serving when in closed position to prevent said member from arresting the operation of the motor-driven element, means causing said member to engage said motor-driven element when said member is free of said gate or plug, and a stop limiting the movement of said member away from the path of said motor-driven element.

In witness whereof I hereunto subscribe my name this 14th day of October, A. D. 1905.

HARRY B. ROUSE.
